Geo. P. Kimmel

ATTORNEY.

UNITED STATES PATENT OFFICE

WILLIAM MACDONALD, OF DENNISON, OHIO

COMBINED PRINTING AND COLOR-APPLYING ELEMENT AND METHOD OF MANUFACTURING THE SAME

Application filed April 17, 1929. Serial No. 355,821.

This invention relates to a combined printing and color applying element, as well as the method of manufacturing the same, and the invention has for its object to provide, in a 5 manner as hereinafter set forth, a printing form, plate or cylinder having interposed therein and as a part thereof, a color applying means for automatically applying color, when desired to the work during the operation of printing the latter from the form, 10 plate or cylinder.

As is well known in the art of printing, especially in newspaper work, a cylindrical printing form or plate is cast with its impressing portions derived from an asbestos form which surrounds and is capable of snapping away from the form or plate after the casting has been completed. One of the objects of the invention is to removably combine 15 with the form or plate, one or more solid dummies, each corresponding in area to and providing openings when removed from the casting for the reception of a color applying means to form a part of the combined printing and color applying element.

A further object of the invention is to provide, in a manner as hereinafter set forth, a new and novel form of color applying means for insertion into the body of and be bodily 20 carried by a printing plate, form or cylinder.

A further object of the invention is to provide, in a manner as hereinafter set forth, a new and novel form of color applying means including a spring controlled, 25 depressible, normally seated discharge means capable of being shifted to open position for the application of color to the work during the operation of the bed cylinder and the printing form of the press or machine on the 30 passage of the work between the bed cylinder and the printing form.

Further objects of the invention are to provide, in a manner as hereinafter set forth, a color applying means for the purpose referred to which is simple in its construction and arrangement, strong, durable, thoroughly efficient in its use, readily installed with respect to a printing cylinder, form or plate and inexpensive to manufacture.

With the foregoing and other objects in

view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view in section of a printing roll or plate of cylindrical form provided with an opening closed by a removable dummy or block.

Figure 2 is a fragmentary view in longitudinal section of a combined printing and color applying element in accordance with this invention.

Figure 3 is a fragmentary view in top plan of a combined printing and color applying element in accordance with this invention.

Figure 4 is a fragmentary view partly in section and elevation illustrating a combined printing and color applying element in accordance with this invention arranged in position with respect to a bed roll between which and the element the work is adapted to pass.

The printing plate, form or cylinder 1 is cast from lead in a known manner, and during the casting operation one or more metallic blocks 2, termed dummies are secured to and surrounded by the body of the casting. The dummy 2 is of the desired length and is of slightly less thickness than that of the body of the casting, so that the lead will extend around the edges of the dummy and not weaken the casting. The ends of the dummy 2 are oppositely beveled. The outer and inner faces of the dummy 2 conform in contour to the outer and inner faces of the casting which provides the printing plate, form or cylinder 1. When the dummy or dummies 2 is or are removed, the printing plate, form or cylinder 1 is provided with one or more openings 3 of an area to snugly receive a spring controlled color applying device or means which, when in position is bodily car-

100

ried with the printing plate, form or cylinder 1 and provides for applying color at the points desired with respect to the work during the printing operation.

5 The color applying device may be formed with one or more normally closed outlets for the color, and each outlet is controlled by a normally seated, spring controlled valvular means therefor, and with said means extended from the color applying device to be engaged and pressed inwardly by the bed roller 4 of the press, during the operation of the form 1 and roller 4 and when the work, not shown is travelling between the form 1 and roller 4 to be compressed from form 1.

10 The opening 3 provided by dummy 2 when the latter is removed conforms in contour to the color applying device referred to generally at 5. The oppositely disposed beveled 20 ends of the dummy 2 are indicated at 2'. The color applying device conforms in contour to that of the dummy 2 and comprises a receptacle including a body portion open at its rear. The body portion consists of an 25 outer wall 6, a pair of side walls 7, 8, a pair of end walls 9, 10. A closure plate 11 is employed for closing the rear of the body portion, and a sealing strip or gasket 12 is interposed between the plate 11 and the rear 30 edges of the side and end walls. The outer wall 6 of the receptacle is integral with the side and end walls.

When the device 5 is mounted in opening 3 the outer wall or front of the receptacle 35 is slightly inset with respect to the outer face of form 1. The receptacle in connection with the closure plate 11 provides a reservoir adapted to contain a body of a liquid coloring medium 13.

40 The color applying device 5 is illustrated as being provided with a series of valve controlled discharge means for the color medium 13, but it is to be understood that the number thereof can be decreased or diminished. 45 Each of the valve controlled discharge means consists of a sleeve 14 having a reduced, peripherally threaded outer portion 15 and with the outer end of said portion 15 inset as at 16 to provide a stop for a globular 50 valve 17 which is arranged within the sleeve 14. The forming of the sleeve 14 with the reduced outer portion 15 provides a shoulder 18.

Arranged within the sleeve 14 and bearing against the valve 17 is a coiled spring 19 which is retained within the sleeve 14 by a transversely extending retaining pin 20. The outer wall or front wall 6 of the receptacle is formed with a number of openings 60 corresponding to the number of the sleeves 14 and as shown the wall 6 has three spaced openings as indicated at 21. The wall of each of said openings is threaded. The reduced portion 15 of the sleeve 14 extends 65 through an opening 21 and threadedly en-

gages with the wall of the latter. When a sleeve 14 is secured to the wall 6 the shoulder 18 abuts against the inner face of such wall. The outer ends of the sleeves 14 project from the outer face of wall 6 and the valves 17 when closed project slightly beyond the outer 70 face of the form 1.

75 The invention provides for the color applying device being interposed in the form 1 and further provides when the form 1 is cast to have it set up with openings of the desired area to snugly receive the color applying means or device.

80 When the valve or valves 17 is or are depressed the suction created by the revolving of the roller 4 will assist in the feed of the 85 color medium 13 which also will feed by gravity when the valve or valves 17 is or are depressed inwardly to provide for the opening of the outer end or ends of the sleeve or sleeves.

90 The plate 11 is removably connected by the holdfast devices 22 to enable the convenient filling of the receptacle when required. The receptacle will be wedgingly secured to the end walls of the openings 3. On discharge of the liquid 13 it will be conducted by the sleeve or sleeves towards the work and will be applied on the latter when a valve or the valves is or are depressed.

95 It is thought the many advantages of a combined printing and color applying element in accordance with this invention, as well as the method of manufacturing the same can be readily understood, and although 100 the preferred embodiment of the invention is as illustrated and described, yet it is to be understood that changes in the details can be had which fall within the scope of the invention as claimed.

105 What I claim is:

110 1. A method of manufacturing a combined printing form and color applying element consisting in casting a printing form around a removable bevelled end dummy corresponding in contour to that of a color applying device, removing said dummy to provide a color applying device receiving opening, and then securing in said opening a color liquid reservoir having valve controlled outlet 115 means projecting beyond the outer face of the form.

120 2. A method of manufacturing a combined printing form and color applying element consisting in casting a printing form around a removable dummy corresponding in contour to that of a color applying device, removing said dummy to provide a color applying device receiving opening, and positioning 125 in abutting relation with respect to the walls of said opening and inwardly of the outer face of the form a color liquid reservoir having valve controlled outlet means projecting beyond the outer face of the form.

130 3. In combination a printing form having

an opening, a receptacle constituting a color liquid reservoir positioned in said opening, one or more sleeves secured in the outer wall of said receptacle to provide color outlet means, and depressible, spring controlled valves mounted in said sleeves for normally closing them and projecting beyond the outer face of the form in the path of a depressing means therefor to open the sleeves for discharge.

4. A color applying device comprising a receptacle adapted to be mounted in and having its outer face conforming in contour to the outer face of a printing form, said receptacle providing a color liquid reservoir, a sleeve secured to and extending through the outer wall of the receptacle and providing for discharge of color from the latter, and a depressible, spring controlled valve carried by said sleeve for normally closing it and adapted to normally project in the path of a depressing means therefor to open the sleeve for discharge of color.

5. A color applying device comprising a receptacle adapted to be mounted in and having its outer face conforming in contour to the outer face of a printing form, said receptacle providing a color liquid reservoir, a sleeve secured to and extending through the outer wall of the receptacle and providing for discharge of color from the latter, and a depressible, spring controlled valve carried by said sleeve for normally closing it and adapted to normally project in the path of a depressing means therefor to open the sleeve for discharge of color, said receptacle having a removable inner wall carrying a sealing member.

6. A color applying device comprising a receptacle adapted to be mounted in and having its outer face conforming in contour to the outer face of a printing form, said receptacle providing a color liquid reservoir, a sleeve secured to and extending through the outer wall of the receptacle and providing for discharge of color from the latter, and a depressible, spring controlled valve carried by said sleeve for normally closing it and adapted to normally project in the path of a depressing means therefor to open the sleeve for discharge of color, said receptacle being of rectangular contour and having its ends inwardly beveled from rear to front.

7. In combination a printing form having an opening, a receptacle constituting a color liquid reservoir positioned in said opening, one or more sleeves secured in the outer wall of said receptacle to provide color outlet means, and depressible, spring controlled valves mounted in said sleeves for normally closing them and projecting beyond the outer face of the form in the path of a depressing means therefor to open the sleeves for discharge, said opening being of rectangular contour and having its end walls oppositely

beveled, said receptacle conforming in contour to the shape of said opening and snugly engaging the wall of the latter.

In testimony whereof, I affix my signature hereto.

WILLIAM MACDONALD.
